OIL BURNER

Allan B. Morton, Portsmouth, Va.

Application January 18, 1939, Serial No. 251,607

17 Claims. (Cl. 158—91)

This invention relates to oil burners and more particularly to a pot type, variable flame oil burner.

An object of this invention is to provide an improved burner structure for heaters which is so constructed that the flow of fuel to the burner is controlled simultaneously with the control of air to the burner, to produce an efficient combustion of fuel in a flame of controlled size.

Another object of this invention is to provide an improved burner wherein a substantially stationary cylinder is provided in the pot and a movable cylinder is adjustable relative to the stationary cylinder, each of the cylinders being provided with air openings and the movable cylinder is operatively connected to a movable valve member associated with the fuel line so as to simultaneously regulate the rate of the delivery of the air and fuel to the burner pot and the longitudinal extent of the pot throughout which the air is introduced.

A further object of this invention is to provide an adjustable means for controlling not only the amount of air but the longitudinal area throughout which the air is delivered to an oil burner, which means may be manually adjusted.

A still further object of this invention is to provide an adjustable air controlling means wherein the adjustment is effected automatically or thermostatically in accordance with the heat generated by the burner.

To the above objects and to others which may hereinafter appear, the invention consists of the novel construction, combination and arrangement of parts as will be more specifically referred to and as illustrated in the accompanying drawings, wherein is disclosed an embodiment of the invention, but it is to be understood that changes, modifications and variations may be resorted to which fall within the scope of the invention as claimed.

In the drawings:

Figure 1 is a detail top plan partly broken away and in section showing a burner structure constructed according to an embodiment of this invention.

Figure 2 is a sectional view taken on the line 2—2 of Figure 1.

Figure 3 is a fragmentary sectional view taken on the line 3—3 of Figure 2.

Figure 4 is an enlarged sectional view taken on the line 4—4 of Figure 2.

Figure 5 is a sectional view similar to Figure 2 of a modified form of burner structure.

Figure 6 is a fragmentary vertical section part-

ly in detail of a further modification of this invention.

Figure 7 is a fragmentary vertical section of a further modification of this invention.

Figure 8 is a fragmentary side elevation of a modified air controlling means wherein the openings are of equal size.

Figure 9 is a vertical section of a further modification of this invention, and

Figure 10 is a vertical section of a further modification of this invention.

In the form of the invention shown in Figures 1 to 4, a fire pot, represented generally at 10, is provided with an outer cylindrical side wall, a bottom wall 11 and an inner cylindrical side wall 15 defining an annular combustion chamber 13 between the cylindrical side walls and above the bottom 11. The bottom wall is provided at its radially inner margin with a downwardly projecting annular flange 12 which is connected to a base housing 14. The inner cylindrical side wall 15 is secured at its lower end within the circle defined by the annular flange 12 and extends upwardly into the interior of the fire pot. The cylindrical inner side wall member 15 is provided adjacent the lower portion thereof with a transversely extending fuel line 16 which is connected to a vertical fuel pipe 17. The transverse pipe 16 opens through the wall 15 into the well or concave bottom member 11 so that liquid fuel flowing through the pipe 16 will enter the well 11. A rotatable tubular valve member 18 is positioned within the vertical pipe 17 and at its lower end, the pipe or valve member 18 engages against a plug member 19 which is threaded into the lower end of the pipe 17. The pipe 17 at a point upwardly from the lower end thereof is provided with a port 20 and a nipple 21 is connected to the lower portion of the pipe 17 and communicates with the port 20. A fuel supply line L is adapted to be threaded into the nipple 21 and is connected at the opposite end to a suitable source of liquid fuel supply. The cylindrical valve member 18 is provided with outlet ports 22 which are adapted to register with the pipe 17 so that fuel flowing upwardly in the valve member 18 will enter the outlet pipe or pipes 16. In the present instance, there are disclosed two outlet pipes 16 which are diametrically opposed and extend diametrically across the space within the inner side wall 15. The valve member 18 adjacent the upper portion thereof is provided with a pilot air port 22' and the upper end of the valve member 18 is provided with a substantially square shank or head 23. The side wall member 15 is provided

with a plurality of circumferentially and vertically spaced apart air openings 24 which are preferably of equal size. An inner air controlling cylinder or air controlling valve 25 is rotatably mounted within the cylindrical side wall or stationary valve member 15 and the cylindrical member 25 is provided with a plate 26 at the upper end thereof, which at its marginal portions projects beyond the outer surface of the inner valve member 25 and engages the upper end of the outer member 15. A gasket 27 is interposed between the upper end of the outer member 15 and the under-surface of the flange 28 formed by the projecting portion of the plate 26. The rotatable valve member 25 is provided with a plurality of circumferentially spaced apart openings 29, and these openings 29 are arranged in superposed series with each row of openings slightly smaller or shorter in length than the preceding row, so that when the valve member 25 is rotated the lowermost air openings 24 in the outer member 15 will communicate with the interior of the inner valve member 25 and continued rotation of the inner member 25 will bring additional series of openings 29 into registry with the additional series of openings 24 in the outer member 15. In this manner, the amount of air flowing upwardly through the inner member 15 can be very finely regulated by rotation of the inner member 25 relatively to the outer member 15. Moreover, the elevation of air delivery relative to the bottom of the combustion chamber and the area longitudinally of the pot throughout which the air is introduced may be increased and decreased at will, simultaneously with an increase or decrease of the rate of fuel delivery. Hence, when the rate of fuel delivery is low, air will be introduced into the combustion chamber only through the lower openings, thereby supporting a flame 40 burning immediately above said openings. When the rate of fuel delivery is raised, additional rows of openings are rendered operative to deliver additional air at higher elevations and throughout a greater area longitudinally of the combustion chamber, with the result that a flame of increased size is supported for combustion at a higher elevation by the delivery of greater amounts of air therebelow. Upon a decrease in fuel delivered, the amount, longitudinal area, 45 and elevation of the air delivery, is correspondingly lower, to support a low burning flame at a lower elevation. The inner member 25 is provided with a diametrically disposed bar 30 which is provided with a bushing or nut member 31 engaging the shank 23 so that rotation of the valve member 25 will effect simultaneous rotation of the liquid valve member 18. The valve member 25 is provided with a bar 32 which projects down below the lower end of the stationary member 15 and terminates within the housing or base member 14. The inner end of the valve controlling lever 33 is connected as at 34 to the lower end of the bar 32 and this lever 33 projects longitudinally of the housing or base member 14 and projects outwardly through an opening 35 provided within the front wall 36 of the base member 14. The opening member 35 permits air to freely enter the lower housing 14 and then pass upwardly into the rotatable member 25. The outer end of the lever 33 is provided with an L-shaped extension or pointer 37 projecting over the top wall 38 of the base member 14 so that the top wall 38 may be provided with graduations by means of which the degree of opening of the holes 24 and 29 can be readily

determined and controlled. The lower end of the valve member 18 is provided with an elongated opening 39 which is adapted to communicate with the opening 20 in the nipple 21 in order to permit the liquid fuel to enter the interior of the valve member 18.

The supply of liquid fuel to the well 11 is controlled by the circumferentially elongated opening 39 in the tubular valve 18, which openings is at all times at least partially in registry with the port 20 in the nipple 21. The valve 18 is preferably provided with four openings 22 which are at all times at least partially in registry with the fuel delivery conduits 16. When the air controlling valve 25 has been moved to a position closing all of the air delivery ports, the valve 18 will be in a position to admit only a small supply of oil, sufficient to maintain a flame of pilot size above the bottom well 11. Air to support this flame is drawn into the combustion chamber by passage through the pilot air ports 22', from which point it flows downwardly in the hollow interior of the valve 18 and outwardly through the conduits 16 to the well 11, where it combines with the fuel and burns.

In Figure 5, there is disclosed a slightly modified form of this invention wherein the fire pot 10^a is provided with a bottom well 11^a similar to the bottom well 11 and which forms a well in which liquid fuel is adapted to be discharged. The inner wall 15^a of the combustion chamber is positioned concentrically of the fire pot 10^a, being secured at its lower end to a flange 12^a formed in the center of the well 11^a. A vertically disposed pipe or valve housing 17^a is provided with a pair of radially disposed outlet connections 16^a, which at their outer ends are secured to the stationary member 15^a and communicate with the well 11^a.

The fire pot 10^a is secured by means of the flange 12^a to the top wall 38^a of a base member 14^a. The inner member 25^a is provided with a top wall 26^a which is fixed to the upper end thereof and the side wall of the member 15^a is provided with a plurality of circumferentially spaced apart openings 24^a which are arranged in vertically spaced apart series. An inner air controlling valve member comprising a cylindrical member 25^a is movably mounted in the outer member 15^a and is provided with a plurality of circumferentially spaced apart openings 29^a which are arranged in vertically spaced apart series with the lowermost of the openings 29^a of a larger size and the succeeding openings gradually decreasing in size so that when the inner member 25^a is vertically moved to its uppermost position, the uppermost series of openings 29^a will be in registry with the uppermost openings 24^a, and all of the preceding openings 29^a will also be in registry with the preceding openings 24^a. A vertically movable valve member 18^a is slideable in the stationary member 17^a and is provided with a pair of opposed ports 22^a which are adapted to communicate with the outlets 16^a so that the fuel entering the tubular valve member 18^a may pass through the radial connections 16^a and then into the well 11^a. The movable valve member 18^a is provided at its upper end with a stem 23^a, and a diametrically disposed bar 30^a is carried by the inner valve member 25^a and engages the stem 23^a. The bar 30^a may be locked on the stem 23^a by means of a cotter pin or locking member 40. The valve member 18^a is provided at a point above the fuel conduit 16^a with a pilot opening 22^b. The lower end of the valve

member 18^a is provided with an inlet port 41 communicating with a nipple or boss 21^a carried by the housing 17^a and to which a fuel pipe line L is adapted to be connected. The lower end of the housing 17^a is closed by means of a bottom wall 42 so that fuel entering the nipple 21^a will pass through the port 41 and then upwardly through the valve member 18^a and out through the conduits 16^a into the wall 11^a.

10 The inner or movable air controlling valve member 25^a is provided adjacent the lower portion thereof with an elongated slot 43 in which the conduits 16^a are loosely received so that the valve member 25^a may be freely moved vertically with the valve member 18^a. An air valve controlling lever 44 provided with a bifurcated inner portion 45 is rockably mounted on a pivot 46 carried by the housing or base member 14^a. The bifurcations 45 of the lever 44 are connected as by a link 47 to an arm or extension 48 carried by the lower end of the valve member 25^a. In the present instance, there are two of these arms 48 and two links 47. The housing 14^a has a forward wall 36^a having an opening 35^a through which air may freely pass, and the outer end of the lever 44 is provided with a pointer 37^a so that the degree of opening of the air ports may be readily determined by the position of the lever 44.

20 In Figure 6, there is disclosed a further modification of this invention wherein a fire pot 10^b is provided having a well 11^b, and a stationary combined side wall and valve member 15^b is mounted within the pot 10^b. A top wall 26^b is secured to the top of the outer member 15^b and the outer member 15^b is provided with a plurality of circumferentially spaced apart openings 24^b. These openings 24^b are arranged in vertically spaced apart series and are preferably of equal size. An inner or vertically movable air controlling valve member 25^b provided with a plurality of graduated openings 29^b is mounted within the outer member 15^b. The inner member 25^b is fixedly secured as by rivets or other suitable fastening devices to the lower end of the outer member 15^b, and preferably this inner member 25^b is constructed of metal having a coefficient of expansion different from the coefficient of expansion of the outer member 15^b so that when these two members are heated, the temperature 30 will expand the metal at different rates in order that the openings 29^b will gradually be brought into registry with the openings 24^b in proportion to the temperature generated within the fire pot 10^b. The fuel for the fire pot 10^b passes through 35 a valve structure 17^b and then through radial conduits 16^b similar to the conduits 16. The fire pot 10^b is mounted on the inner end of an air housing or base member 14^b similar to the housing 14.

40 The top plate 26^b is connected to the valve plug 18^b by means of an elongated rod 82 which is fixed at its lower end to the valve plug 18^b and is provided with a threaded upper end 83 on which an adjusting nut 84 is mounted. In this manner, the degree of opening of the valve plug 18^b can be readily adjusted so that expansion of the outer member 15^b will bring into registry the openings 24^b and 29^b and also the orifice of valve 17^b.

50 In Figure 7, there is disclosed a further modification of this invention wherein the movement of the inner sleeve or air controlling member 25^c is thermostatically controlled. The inner member 25^c is mounted within an outer or stationary member 15^c secured in the lower portion of the

fire pot 10^c. The outer member 15^c is provided with a plurality of circumferentially spaced apart openings 24^c which are of equal size and are arranged in vertically spaced apart series. The inner member 25^c is provided with a plurality of circumferentially spaced apart openings 29^c which are arranged in vertically spaced apart series with the openings graduated or decreasing in size in an upward direction. The inner member 25^c is thermostatically controlled by means of a wafer or expandable concave member 50 which at its marginal portions engages an upwardly flared rim 51 fixed to the outer member 15^c. The valve operator 50 may be provided with a marginal flange 55 engaging a marginal flange 56 carried by the flared rim 51 and the flange 55 may be secured to the flange 56 by means of fastening members 57. The valve operator 50 is connected to the valve plug 18^c by a threaded rod 52 which extends through the operator 50 and is secured at its lower end to the valve plug 18^c. The rod 52 extends through the bar 53 and the rod 52 is fixed relative to the bar 53 by a pair of lock nuts 58 and 59. The inner member 25^c is provided with the bar 53 which extends diametrically across the inner member 25^c and is fixed at its ends to the inner member 25^c. A nut 54 is threaded onto the upper end of the rod or bolt 52 and bears against the upper side of the plate 50 so that the inner member 25^c and the valve plug 18^c may be correctly adjusted to secure the desired registry between the openings 24^c and 29^c and the orifice in valve 17^c. The inner member 25^c is provided with an elongated and downwardly opening slot 55 which engages about the fuel member 16^c which is connected to the valve housing 17^c. Expansion of the plate 50 and the flared rim 51 will be in an upward and outward direction, as shown by the arrows in the upper portion of Figure 7 during the increasing in temperature within the fire pot 10^c so as to thereby raise the inner member 25^c to the proper position in order to admit air through the openings 29^c and 24^c to the fire pot 10^c.

55 In the use and operation of this burner, the burner structure shown in Figures 1 to 4 inclusive is adapted to be mounted in a suitable housing and connected by means of the pipe 11 to a source of fuel supply. The pilot may be burning continuously and when the air valve controlling lever 33 is swung horizontally, the valve member 18 is rotated to the selected open position wherein the liquid may flow through the hollow valve member 18 and the radial conduits 16 into the fire pot 10. By means of a construction of this kind, the quantity of air which is admitted to the fire pot 60 is regulated in accordance with the degree of opening of the fuel valve 18 so that at any opening of the valve 18, the air which is admitted to the fire pot 10 will be in proper proportion and at the optimum position so as to thereby obtain the complete combustion of the fuel. The lowermost openings 24 of the lower series are openings initially brought into registry with the lowermost series of openings 29 of the inner-sleeve or valve member 25 so that when the blaze is at its lowest point or position, the air admitted for combustion purposes is admitted closely adjacent the fuel well 11. As the quantity of fuel increases by rotation of the valve member 18, the air controlling valve member 25 will simultaneously rotate therewith and bring into registry additional openings 29 above the initially operative openings. When the valve member 18 is at its fullest opened position, all of the openings 24 are 65 70 75

in registry with all of the openings 29 and the air is admitted to the combustion chamber throughout substantially the entire longitudinal area of the inner side wall 15. It will thus be seen that 5 the quantity of air admitted and its area of introduction for combustion purposes are regulated in accordance with the quantity of fuel and that the air is initially admitted in the fire pot in substantially the ratio of the amount of fuel admitted, and in addition is admitted in proportion 10 to the height of the blaze in the fire pot. In this manner, the correct combustion of the fuel can be obtained at all times so that the burner will not smoke. The fuel entering the supply line L may 15 pass through this line under gravity or, if desired, may be forced through the line L and the valve member 18, entering the well 11.

Heretofore, in burners of this type, the air admitted for combustion purposes is admitted by 20 means of a movable damper, but while this damper may be regulated manually so as to obtain the desired combustion of the fuel, the regulation of the damper is not in direct proportion to the quantity of fuel, nor is the damper actuated simultaneously with the opening or closing 25 of the fuel valve.

The burner structure disclosed in Figure 5 is also manually regulated by means of the vertical 30 rocking of the lever 44 which moves the valve member 25^a and also moves therewith the valve member 18^a.

In Figure 8 there is disclosed the wall 15^d of a stationary valve member having openings 24^d therein arranged in staggered relation. This 35 construction may be used in any of the previously described constructions, it being understood that where this construction is used, the movable valve will have the openings therein similarly arranged.

40 In Figure 9 there is disclosed a further modification of this invention wherein a fire pot 10^e is shown having a well 11^e which is provided in the bottom thereof with a fuel intake pipe 16^e discharging into the bottom of the well 11^e. The 45 upper end of the fire pot 10^e is provided with an annular flange 56 which is formed by bending the material forming the cylindrical side wall 15^e of the fire pot downwardly so as to provide an annular rim or shoulder 57 extending upwardly 50 from the flange 56. The flange 56 rests on a supporting plate 58 secured to the wall 59 forming the heater. A plate 60 provided with a central opening 61 and a down turned marginal flange 62 engages over the upper open end of the 55 fire pot 10^e. The plate 58 is provided with a depending annular flange 63 which is secured by fastening devices 64 in the form of rivets or the like to the outer wall 59 of the heater.

The fuel pipe 16^e is adapted to be connected 60 to a suitable source of fuel supply and may be provided with a valve which may be manually controlled for regulating the flow of the liquid fuel to the intake pipe 16^e and the well 11^e. The side wall of the fire pot 10^e is provided with a 65 plurality of circumferentially arranged air openings 24^e which are arranged in vertically spaced apart series or rows with the openings 24^e of substantially equal size. An outer cylindrical shell or valve member 25^e is rotatably disposed 70 about the cylindrical shell 15^e and is provided with a plurality of circumferentially arranged air openings 29^e which are graduated in size from the bottom to the top of the outer member 25^e so that initially the lowermost openings 24^e will 75 communicate with the lowermost openings 29^e

and then when the outer member 25^e is rotated an additional distance, additional series of openings 24^e will come into registry with the additional series of openings 29^e. The outer member 25^e is supported for rotation relative to the inner 5 or stationary member 10^e by means of bolts or fastening members 65 which extend through elongated openings 66 provided in the outer or stationary member 25^e and are then threaded into the side wall 15^e of the pot 10^e. The inner member 15^e is held against rotation relative to the outer member 25^e by means of bolts or fastening devices 67 which extend through the flange 56 and the supporting plate 58. The outer member 25^e is provided with a depending extension or arm 68 10 and a handle or operator 69 is provided with a right-angular extension 70 at the inner end thereof which is secured to the extension 68 by means of a fastening member 71 in the form of a rivet or bolt. The operator 69 extends through an opening 72 provided in the outer jacket 59 15 through which air may also pass so that the outer rotatable shell or valve member 25^e may be readily regulated from the exterior of the jacket 59.

In Figure 10, there is disclosed a further modification of this invention wherein a fire pot 10^f is supported from a supporting plate 58^f. The plate 58^f is provided with a marginal flange 63^f secured by fastening members 64^f to the outer wall or jacket 59^f of the heater. The plate 58^f is provided with a central opening 73 through which the fire pot 10^f extends. The fire pot 10^f is provided with an annular flange 56^f formed by bending the material forming the cylindrical side wall 15^f downwardly and then outwardly thereby providing a shoulder 57^f at the upper end of the fire pot 10^f. The flange 56^f may be secured to the plate 58^f by means of bolts or fastening members 67^f. The fire pot 10^f is provided with a well 11^f in the bottom thereof and a fuel intake member 16^f discharges into the well 11^f. An outer rotatable or controlling cylinder 25^f is disposed about the cylindrical wall 15^f of the inner member and is supported against 40 endwise movement from the inner member 15^f by means of bolts or supporting members 65^f which extend through elongated slots 66^f provided in the outer member 25^f. The fastening member 65^f may be threaded into the cylindrical 45 wall 15^f or otherwise securely fastened thereto. The inner member 10^f is provided with a plurality of circumferentially arranged air openings 24^f which are preferably of equal size and are arranged in vertically spaced apart series. 50 The outer member 25^f is provided with a plurality of circumferentially arranged graduated openings 29^f which are also arranged in vertically spaced apart series and adapted to progressively register with the openings 24^f upon 55 rotation of the outer member 25^f relative to the inner stationary member 15^f. An elongated operator in the form of a rod or lever 69^f provided with a right-angular inner end 70^f is secured by means of fastening members 71^f to the outer member 25^f. The lever or operator 69^f extends through an opening 72^f provided in the outer wall 59^f, and in this manner the outer member 25^f may be manually controlled and 60 rotated relative to the inner member 15^f.

A valve member 17^f having a nipple 14 is secured to the fuel pipe 16^f and is provided with a rotatable hollow plug 18^f which is provided with a fuel port 22^f. The plug 18^f is also pro- 75

vided with an air opening 15 so as to provide sufficient air for mixture with the fuel vapors to maintain a pilot light in the burner. The plug 18¹ is provided with an intake opening 41¹ adapted to register with a port 20¹ carried by a nipple 21¹. The nipple 21¹ is adapted to be secured to a fuel pipe line L which is connected to a source of fuel supply.

The plug 18¹ is provided with a square head 10 or extension 23¹ on the upper end thereof and a nut member or bushing 31¹ is adapted to engage the head 23¹. A laterally extending arm 76 is fixed to the nut or bushing 31¹ and is provided with an elongated slot 77. A valve controlling bolt 78 is carried by the lever or operator 69¹ and is provided with an extension 79 engaging in the slot 77. A nut 80 is threaded onto the bolt 78 and provides a means whereby the bolt 78 may be adjusted longitudinally of a slot 81 provided in the lever 69¹ and through which the bolt 78 extends. In this manner, the degree of opening of the valve plug 18¹ may be correctly adjusted with relation to the openings 24¹ and 29¹ by adjusting the bolt 78 longitudinally of the lever 69¹.

What I claim is:

1. An oil burner comprising a fire pot open at the top, a well in the bottom of the fire pot, means for discharging liquid fuel in said well, said fire pot having an air opening through said well, a stationary air valve member rising from said opening and provided with a series of vertically spaced apart air openings, a movable air valve member in said stationary member provided with a series of vertically spaced apart graduated openings adapted to progressively register with said air openings in said stationary member, and means connected to said movable member for moving said movable member relative to said stationary member.

2. An oil burner comprising a fire pot open at the top, a well in the bottom of the fire pot, means for discharging liquid fuel in said well, said fire pot having an air opening through said well, a stationary air valve member rising from said opening and provided with a series of vertically spaced apart air openings, a movable air valve member in said stationary member provided with a series of vertically spaced apart graduated openings adapted to progressively register with said air openings in said stationary member, and manually operable means connected to said movable member for moving said movable member relative to said stationary member.

3. An oil burner comprising a fire pot open at the top, a well in the bottom of the fire pot, means for discharging liquid fuel in said well, said fire pot having an air opening through said well, a stationary air valve member rising from said opening and provided with a series of vertically spaced apart air openings, a movable air valve member in said stationary member provided with a series of vertically spaced apart graduated openings adapted to progressively register with said air openings in said stationary member, means connected to said movable member for moving said movable member relative to said stationary member, and means connected to said movable member and said fuel discharging means for controlling the quantity of fuel discharged into said well in proportion to the quantity of air admitted to the fire pot.

4. An oil burner comprising a fire pot open at the top, a well in the bottom of said fire pot, a fuel

valve connected to said well and to a source of fuel supply, an air intake housing secured to said fire pot, a stationary sleeve secured to said fire pot and communicating with said housing, said sleeve having a plurality of circumferentially arranged air openings disposed in vertically spaced apart series, an inner air controlling sleeve within said first sleeve and provided with graduated openings therein adapted to progressively register with said first openings, said valve including a plug provided with a stem, means connecting said stem with said inner sleeve, and means connected to said inner sleeve for moving said inner sleeve relative to said first sleeve while simultaneously moving said plug to thereby control the flow of fuel in proportion to the registry of the openings in said sleeves.

5. An oil burner comprising a fire pot open at the top, a well in the bottom of said fire pot, a fuel valve connected to said well and to a source 10 of fuel supply, an air intake housing secured to said fire pot, a stationary sleeve secured to said fire pot and communicating with said housing, said sleeve having a plurality of circumferentially arranged air openings disposed in vertically 15 spaced apart series, an inner air controlling sleeve within said first sleeve and provided with graduated openings therein adapted to progressively register with said first openings, said valve including a plug provided with a stem, a 20 diametrically disposed bar fixed to said inner sleeve and connected to said stem in a manner to thereby move said stem and plug with said inner sleeve, and means connected to said inner sleeve for moving said inner sleeve relative to 25 said first sleeve while simultaneously moving said plug to thereby control the flow of fuel in proportion to the registry of the openings in said sleeves.

6. An oil burner comprising a fire pot open 40 at the top, a well in the bottom of said fire pot, a fuel valve connected to said well and to a source of fuel supply, an air intake housing secured to said fire pot, a stationary sleeve secured to said fire pot and communicating with 45 said housing, said sleeve having a plurality of circumferentially arranged air openings disposed in vertically spaced apart series, an inner air controlling sleeve within said first sleeve and provided with graduated openings therein adapted to progressively register with said first openings, means supporting said inner sleeve for rotation within said first sleeve, means connecting said inner sleeve to said valve to simultaneously open or close said valve upon rotation of said 50 inner sleeve, and means connected to said inner sleeve and extending outwardly through said air housing for rotating said inner sleeve.

7. An oil burner comprising a fire pot open 60 at the top, a well in the bottom of said fire pot, a fuel valve connected to said well and to a source of fuel supply, an air intake housing secured to said fire pot, a stationary sleeve secured to said fire pot and communicating with said 65 housing, said sleeve having a plurality of circumferentially arranged air openings disposed in vertically spaced apart series, an inner air controlling sleeve within said first sleeve and provided with graduated openings therein adapted 70 to progressively register with said first openings, a vertically rockable operating lever carried by said housing, means connecting one end of said lever to said inner sleeve, and means connecting said inner sleeve to said valve where-

- by to operate said valve simultaneous with the vertical movement of said inner sleeve.
8. A fuel burner comprising a fire pot provided with a cylindrical wall having openings therein, a well in the bottom of said fire pot, a cylindrical air valve provided with a plurality of graduated openings adapted to progressively register with said first openings, means supporting said air valve for movement relative to said fire pot, means for moving said air valve relative to said fire pot, and means discharging fuel into said well.
9. A fuel burner comprising a fire pot provided with a cylindrical wall having openings therein, a well in the bottom of said fire pot, supporting means fixed to said fire pot, a cylindrical air valve about said fire pot and provided with a plurality of graduated openings adapted to progressively register with said first openings, means engaging said first pot and said air valve for supporting said air valve for limited rotary movement, means discharging liquid fuel in said well, and means for rotating said air valve relative to said fire pot.
- 25 10. A fuel burner comprising a fire pot provided with a cylindrical wall having openings therein, a well in the bottom of said fire pot, supporting means fixed to said fire pot, a cylindrical air valve about said fire pot and provided with a plurality of graduated openings adapted to progressively register with said first openings, means engaging said fire pot and said air valve for supporting said air valve for limited rotary movement, a fuel valve connected to said well, means for rotating said air valve relative to said fire pot, and means connecting said fuel valve with said latter means to thereby control the admission of fuel simultaneously with the operation of said air valve.
- 40 11. A fuel burner comprising a pair of concentric cylindrical members, a well carried by one of said members, each of said members having a plurality of air openings, the openings in one of said members being of substantially equal size, means supporting said members for movement of one relative to the other, and means for moving one of said members relative to the other member, the other of said members having the openings therein so arranged and of 45 such a size as to effect progressive registration of said latter openings with said first openings.
12. An oil burner comprising in combination a fire pot provided with a plurality of spaced air inlet openings, means discharging fuel into said fire pot, and means connected to said fire pot and said first means for admitting air into selected ones of said openings in proportion to the quantity of fuel discharged into said fire pot, said air admitting means including means for 60 completely cutting off the passage of air through the remaining openings.
13. An oil burner comprising a combustion chamber having a side wall provided with openings disposed longitudinally thereof, means for introducing liquid fuel at varying rates into the chamber adjacent one end thereof to be vaporized therein, and means for increasing and decreasing the amount of air introduced into said chamber in proportion to the increase and decrease in the rate of fuel introduced, comprising control means, operatively connected with the first-mentioned means, for progressively increasing and decreasing the longitudinal area of the side wall from said vaporizing end throughout which air is introduced through said openings, as the rate of fuel introduction is increased and decreased.
14. An oil burner comprising a combustion chamber having an end wall and a side wall provided with openings disposed longitudinally thereof, means for introducing liquid fuel in varying rates into the chamber adjacent said end wall to be vaporized therein, and means for increasing and decreasing the amount of air introduced into said chamber in proportion to the increase and decrease of the rate of fuel introduced, comprising control means, operatively connected with the first-mentioned means, for progressively increasing and decreasing the longitudinal area of the side wall from said end wall throughout which air is introduced through said openings, as the rate of fuel introduction is increased and decreased.
- 15 15. An oil burner comprising a combustion chamber having a bottom and a side wall, adjustable means for introducing liquid fuel into the chamber at varying rates to be vaporized therein adjacent the bottom wall, means for introducing air into the chamber through said side wall at a plurality of different elevations, and means, operatively connected to the first-mentioned means, for varying the amount of air so introduced in proportion to variations in the rate of fuel introduction, comprising control means for variably and progressively rendering the air introducing means operative in succession from a lower elevation to a higher elevation upon an increase in the rate of fuel introduction.
- 20 16. An oil burner comprising a combustion chamber having a bottom wall and a side wall, means for introducing liquid fuel into the chamber at varying rates, a plurality of ports for the introduction of air into the chamber arranged in the side wall in a plurality of horizontal rows disposed at different elevations above the bottom wall, and means, operatively connected to the first-mentioned means, for gradually and simultaneously opening the ports in one row and then, simultaneously in each row, and progressively from row to row, opening the ports in the rows thereabove upon increase in the rate of fuel introduction.
- 25 17. An oil burner comprising a combustion chamber having a bottom wall and a side wall having air ports arranged therein in a plurality of vertically spaced horizontal rows, means for introducing oil into the chamber adjacent the bottom wall at varying rates to support a flame of varying size, and valve means for controlling said ports, said valve means being movable in one direction upon an increase in the rate of fuel introduction to open the ports successively, row by row, from a lower row upwardly until substantially all of the ports are open, and being movable in the opposite direction upon a decrease in the rate of fuel introduction to close the ports, row by row, from an upper row downwardly.
